UNITED STATES PATENT OFFICE.

CHARLES E. KENNEDY, OF LAKEVILLE, MASSACHUSETTS, ASSIGNOR TO UNITED SHOE MACHINERY COMPANY, OF PATERSON, NEW JERSEY, A CORPORATION OF NEW JERSEY.

RAND-TURNING MACHINE.

1,190,296.

Specification of Letters Patent.

Patented July 11, 1916.

Application filed November 1, 1915. Serial No. 59,036.

To all whom it may concern:

Be it known that I, CHARLES E. KENNEDY, a citizen of the United States, residing at Lakeville, in the county of Plymouth and 5 State of Massachusetts, have invented certain Improvements in Rand-Turning Machines, of which the following description, in connection with the accompanying drawings, is a specification, like reference characters 10 act on the drawings indicating like parts in the several figures.

This invention relates to machines for imparting a predetermined shape to articles of leather, and more particularly to machines 15 for giving rand strips a form adapted to permit them to be conveniently attached to heels.

As is well known, rands used in the manufacture of boots and shoes are strips of 20 leather which taper transversely to a thin edge. It is a common practice in the art to prepare the rands for the use for which they are intended by giving them approximately the contour which is their final 25 shape when attached to heels. This is effected by bending the rand strip in the plane of the strip into a shape approximating that of the heel to which it is to be attached.

While various kinds of machines have 30 been designed in which the rand strip is bent to the desired shape and then compressed so that it will retain such shape until it is about to be attached to a heel, such machines have been of complicated construction, and slow in operation because the operator 35 is obliged to start and stop the machine, by treadle or otherwise, for each rand strip operated upon. On the other hand, the machines having rotary members for molding 40 rand strips, while being more rapid and less complicated, have given a curved contour to the entire length of the rand and such a shape does not correspond to the ordinary 45 shape of heel and can be fitted thereto only with considerable difficulty and loss of time.

The desired form, which corresponds most closely to the usual shape of heel, is substantially U-shaped and the primary object of 50 the present invention is to provide a simple, rapid and efficient machine for imparting a contour of this nature to rand strips by curving only a portion thereof intermediate 55 between their ends, without affecting the end portions, so that the end portions will retain their original form, which may be sub-

stantially straight or slightly curved, the latter being the case when the rands are made from the skivings produced in the manufacture of certain shapes of heel counters or box toe blanks.

Important features of the present invention consist in providing a rand molding machine with means constructed and arranged to limit the action of the rand molding means to a portion of a rand strip intermediate between its ends, and in providing means to prevent the action of said rand-molding means upon the end portions of the rand strip.

Another feature of the invention consists 70 in having the rand molding members moved periodically into and out of coöperative relation to each other during the continuous operation of the machine so that, without the use of a treadle or any other starting and 75 stopping mechanism, the completed rand may be readily removed from the machine and another rand strip be inserted therein during the time that the rand molding members are out of coöperative relation to 80 each other.

An additional feature of the invention consists in having the rand guide and the rand molding members moved periodically 85 into and out of coöperative relation to each other so that only a portion of the rand strip will be molded. Such a construction also allows the rand strip to be more readily inserted into the machine.

A further feature of the invention 90 consists in providing an adjustable end gage to position a rand strip longitudinally so as to cause the rand molding means to operate upon a predetermined portion of the rand strip. In this way the length of the portions 95 of the rand strip which are not operated upon may be made substantially equal or may be made to bear some other predetermined relation to each other, as is desirable when used on so-called "orthopedic" 100 or "kidney" heels.

While the embodiment of the invention presently to be described consists of a rotary machine having the above features for accomplishing the desired object, it should be 105 understood that some of the features may be embodied in other forms of machines for the purpose without departing from the scope of the invention as defined in the annexed claims.

A machine embodying the invention is illustrated in the accompanying drawings, in which,—

Figure 1 is a perspective view of the complete machine; Fig. 2 is a side elevation of the machine with portions removed in order that certain of the operating parts may be more clearly shown; Fig. 3 is a view similar to Fig. 2 but with the operating parts in a different position; Fig. 4 is a view, partly in section, taken in the vertical plane indicated by the line 4—4 in Fig. 3; Fig. 5 is a detail, partly in section, of the cam and associated parts that control the movement of the presser block; and Fig. 6 is a view of the rand produced by the machine.

The machine is provided with a main driving shaft upon which are located a tight pulley 1 and a loose pulley 2. This shaft, which carries a pinion 3, is intended to be continuously rotated in the direction of the arrow (Fig. 1) while the machine is in use. The pinion 3 drives two gears 4 and 5, each of which is mounted on its individual shaft supported by the framework of the machine. The gear 4 continuously rotates the rand turning head 6, while the gear 5 continuously rotates a cam 7 upon which are two cam tracks.

The cam track 8, by means of the cam roll 9, acting through mechanism about to be described, intermittently moves the rotatable presser block 11 into and out of cooperative relation to the rand turning head 6. This mechanism comprises the lever 10, pivoted near its center at 26, and its associated parts. The ends of the lever are enlarged, and operate in the drilled out bosses 27 and 28. These bosses are slotted on the sides toward the center of the lever, as shown at 29, to allow the lever to pass through the slots into the drilled out portions of the bosses. The rear end of the lever 10 is enlarged and tapped for the adjusting screw 33, the end of which bears against the plunger 34 that carries the cam roll 9. This plunger is prevented from turning in the boss 27 by the screw 35, which engages a longitudinal slot in the top of the plunger. The plunger is thus free to move in and out but the cam roll 9 always remains in proper relation to the cam track 8. A compression spring 22 forces the rear end of the lever inward, thus keeping the end of the screw 33 in contact with the plunger 34 and the cam roll 9 in contact with its cam track 8. The front end of the lever 10 is enlarged and drilled to allow the rod 36, secured to the back of the rotatable presser block 11, to pass through it freely. Between the presser block and the lever 10 a strong compression spring 23 is interposed. The outer end of the rod 36 is threaded for an adjusting nut 37 and check nut 38 and between the nut 37 and the lever 10 a smaller spring 40 is inter-

posed to take up back lash and increase the smoothness of operation. By turning the nut 37, the rod 36 may be drawn through the lever 10 and the spring 23 adjusted to have the desired amount of initial compression 70 which will prevent any axial yielding of the presser block 11 until after the required amount of pressure has been put upon the rand strip by the movement of the lever 10 and presser block 11 toward the rand turning head 6. When the cam roll 9 has reached the raised portion 8^a of the cam track and the front end of the lever 10 has reached the limit of its movement toward the rand turning head 6, the spring 23 will 80 be compressed still more and the presser block can then yield axially to accommodate itself to variations in the thickness of the rand strip. The maximum pressure that will be applied to the rand, depending upon 85 the amount that the spring 23 is finally compressed, is determined by the adjusted position of the screw 33 in the rear end of the lever 10. When this screw 33 is turned inwardly, the compression is increased, as will 90 be understood by an inspection of Figs. 1, 4 and 5. The other cam track 12, by means of cam roll 18 located on the cam lever 13, intermittently reciprocates the connecting link 14 and operates the rand guide 15, moving it into and out of cooperative relation to the rand turning head 6 and the presser block 11. Attached to the mechanism for operating the rand guide and, in this particular construction, attached to the connecting rod, is an end gage 16 for locating the rand strip 17 longitudinally when it is first inserted into the machine. The rotary rand molding members, comprising the rand turning head 6 and the presser block 11, together with the rand guide 15, when in cooperative relation to each other, crimp and mold the rand in the manner usual in such machines and need not be described here in detail.

In order to point out how, by controlling the movements of the rand molding members and the rand guide, only a portion of the rand strip, intermediate between its ends, is operated upon, the operation of the machine 115 will now be described in detail.

With the rand guide and end gage in the position shown in Fig. 2, the rand strip 17 is inserted from above until its lower end rests upon the end gage 16 in the position 120 shown in said Fig. 2. At this time, inasmuch as the cam roll 9 is on the low portion of the cam track 8, the presser block 11 is drawn away from the rand-turning head 6 by the compression spring 22 acting on 125 the pivoted lever 10. This position of the presser block, which is shown in Fig. 4, leaves plenty of room for the rand strip to be inserted between it and the rand turning head. The cam track 12, acting on the cam 130,

roll 18, then moves the cam lever 13, connecting link 14 and rand guide 15 into the position shown in Fig. 3, in which position they remain for substantially half a revolution of the cam. When the rand guide first assumes this position, the raised portion 8^a of the cam track 8 commences to act upon the cam roll 9 and moves the presser block 11 into coöperative relation to the rand turning head 6, the spring 23 being further compressed by this operation so that the presser block may yield axially to accommodate itself to variations in the thickness of the rand strip while putting sufficient pressure 15 on the rand strip to hold it in position for the rand-turning head to crimp it properly. It will be seen that the screw 24 and the slot 25 at the upper end of the end gage provide means for adjusting the end gage so 20 that the crimping operation may start at any desired point longitudinally of the rand strip. After the parts have been brought into coöperative relation to each other, the rand strip is crimped and molded for a 25 limited portion of its length in the manner usual in rotary rand turning machines. When the cam roll 9 drops off the raised portion 8^a of the cam track 8, the pressure of the presser block is removed, the rand 30 turning operation ceases and the completed rand 19 drops upon the bench. The rand guide and end gage are retracted at the same time into the position shown in Fig. 2 and remain in this position for a length of 35 time sufficient to allow a new rand strip to be inserted in the machine, while the rotation of the machine continues without stopping. Thus the rand strips are fed to the machine, one after another, without the 40 necessity of starting and stopping it for each one operated upon. After the completed rand 19 is attached to a heel, the ends 20 of the rand are trimmed off in line with the breast of the heel and the heel is then 45 compressed in a heel compressing machine in the usual way.

Having thus described the invention, what is claimed as new and desired to be secured by Letters Patent of the United States is:—

50 1. A machine of the class described, having, in combination, rand molding means, and means constructed and arranged to limit the action of said rand molding means to a portion of a rand strip intermediate between its ends.

55 2. A machine of the class described, having, in combination, rand molding means, and means constructed and arranged to limit the action of said rand molding means to the longitudinally central portion of the rand strip.

60 3. A machine of the class described, having, in combination, rotary rand molding means, and means constructed and arranged to limit the action of said rand molding

means to a portion of a rand strip intermediate between its ends.

4. A machine of the class described, having, in combination, rand molding means and means constructed and arranged to prevent the action of said rand molding means upon the end portions of a rand strip. 70

5. A machine of the class described, having, in combination, rotary rand molding means and means constructed and arranged 75 to prevent the action of said rand molding means upon the end portions of a rand strip.

6. A machine of the class described, having, in combination, rotary rand molding members and means constructed and arranged 80 to move said rand molding members periodically into and out of coöperative relation to each other to mold a portion only of a rand strip.

7. A machine of the class described, having, in combination, rand molding members, a rand guide and means constructed and arranged to move said rand molding members and rand guide periodically into and out of coöperative relation to each other to mold 90 a portion only of a rand strip.

8. A machine of the class described, having, in combination, rotary rand molding members, a rand guide and means constructed and arranged to move said rand molding 95 members and rand guide periodically into and out of coöperative relation with each other to mold a portion only of a rand strip.

9. A machine of the class described, having, in combination, rand molding means, 100 means constructed and arranged to limit the action of said rand molding means to a portion of a rand strip intermediate between its ends and an adjustable end gage to position the rand strip longitudinally and cause 105 the rand molding means to operate upon a predetermined portion of the rand strip.

10. A machine of the class described, having, in combination, rand molding means, means constructed and arranged to limit the 110 action of said rand molding means to a portion of a rand strip intermediate between its ends and an adjustable end gage to position the rand strip longitudinally and cause the rand molding means to operate upon the longitudinally central portion of the rand strip. 115

11. A machine of the class described, having, in combination, a rotary shaft provided with a rand turning head, a presser block, cam-actuated means for moving said presser 120 block into and out of coöperative relation to said rand-turning head, a rand guide and an adjustable end gage to position a rand strip longitudinally.

12. A machine of the class described, having, in combination, a rotary shaft provided with a rand turning head, a presser block, a rand guide, an adjustable end gage to position the rand strip and means constructed 125 and arranged to move both said presser block 130

and said rand guide periodically into and out of coöperative relation to the rand turning head.

13. A machine of the class described, having, in combination, a rotary shaft provided with a rand turning head, a freely rotatable presser block coaxial with said shaft and yieldingly movable axially, cam - actuated means for moving axially said presser block 10 into and out of coöperative relation to said rand-turning head, a rand guide, and a cam-actuated means for moving said rand guide into and out of coöperative relation to the rand turning head.
14. A machine of the class described, having, in combination, a rotary shaft provided with a rand turning head, a freely rotatable axially movable presser block, means operating periodically for moving axially said 20 presser block into and out of coöperative relation to said rand-turning head, a rand guide for guiding a rand strip between the rand turning head and the presser block, and an adjustable end gage to position the

rand strip so that only a portion thereof intermediate between its ends will be operated upon during the time that the rand turning head and presser-block are in coöperative relation to each other. 25

15. A machine of the class described, having, in combination, a rotary shaft provided with a rand turning head, a rotatable presser block yieldingly movable axially, means, including a cam, a pivoted lever and yielding connections, for moving axially said presser block into and out of coöperative relation to 30 said rand-turning head, a rand guide mechanism, including a pivoted rand guide, a cam, a cam lever and connecting rod, for swinging said rand guide into and out of coöperative relation to the rand turning head 35 and an end gage adjustably secured to said rand guide mechanism to position the rand strip. 40

In testimony whereof I have signed my 45 name to this specification.

CHARLES E. KENNEDY.
